UNITED STATES PATENT OFFICE

2,621,824

MACHINE FOR HANDLING FLANGED PINS

Sylvester L. Gookin, Quincy, Mass., assignor to
 United Shoe Machinery Corporation, Flemington, N. J., a corporation of New Jersey

Application September 13, 1950, Serial No. 184,541

4 Claims. (Cl. 218—5)

1

This invention relates to means for the automatic feeding and orienting of pins and more particularly to an assembling machine having mechanism for feeding one or more pins at a time from a promiscuous supply to a definite assembly position, the pins being either hollow or partially tubular and respectively having an external transverse flange or shoulder portion.

As used herein the term "flanged pin" is intended to denote a hollow, elongated article having an external collar or enlarged portion extending circumferentially, the article not necessarily being headed, pointed or of circular section. Pins of the general form just described are widely used in many industries for different purposes. They serve, for example, as fasteners, ornaments, bearings, as contact elements in electrical devices, and may even function as small containers. The preformed flange on such a pin, depending on the particular application, may be located at one end or intermediate the ends and it may serve as a guide for the pin, aid in its attachment or positioning, or simply be decorative. Whatever the intended use, a common problem arises in automatically manipulating flanged pins in such a manner that they may be consecutively moved from their random positions en masse to a definite position in which they are uniformly oriented for further processing. The problem is naturally more difficult when the pins are so formed that they tend to entangle with or lodge in one another and thereby accumulate and resist orderly arrangement, an important condition to which the invention is specially addressed as will herein-after be explained.

A primary object of the present invention, accordingly, is to provide a pin-handling machine having simple and improved means for consecutively feeding flanged pins from a haphazard supply thereof, the pins to be individually delivered, in uniformly oriented condition to a definite pin-receiving position for further processing.

With this object in view a feature of the invention resides in a pin-working machine comprising a hopper for containing flanged pins, a raceway curvedly extending generally downward from the hopper and in communication therewith freely to conduct consecutively a series of said pins endwise, said raceway having an intermediate slotted portion more nearly horizontally disposed, the slot extending longitudinally and being of a width to enable the pins to be vertically suspended by their flanges in said portion, and percussion means engageable with said

2

portion for assuring that endwise conveyance of said pins is transformed by gravity to uniform sidewise delivery thereof.

A further feature of the invention is the provision in an assembling machine of pin feeding mechanism comprising a hopper provided with an inclined bottom wall having an upstanding radial rib, a dual swingable raceway registering with a port on each side of said rib and contiguous with the lower margin of said wall, the raceway being adapted to accommodate only endwise passage of the pins and having its passageways merging respectively with a groove formed in the bottom wall, and agitating means in the hopper for sweeping the pins against both sides of said rib, into the grooves, and through the ports.

Another feature of the invention is the provision of means at the swingable delivery end of the raceway for accurately positioning the endmost flanged pin therein prior to its release to the action of a reciprocable pin inserting instrumentality. Said means comprises, in an illustrative machine, a spring-pressed, pivotally mounted detent having a pin engaging surface including a slot corresponding to the pin flange, said surface being arranged and adapted to accommodate the endmost pin while other pins bear on it so that it is thereby momentarily positioned and precisely held in vertical or other angularly desired relation to the path of the inserting instrumentality.

The above and other features of the invention including novel arrangements and combinations of parts will now be described in more detail in connection with one embodiment, the specific organization selected for purposes of illustration having application to the problem of feeding and installing flanged contact pins which are to be assembled in electrical devices such as electron tubes. It will be apparent that the invention is not restricted to this particular embodiment or application nor to use with the exact form and type of pin here employed as a contact element. It will be recognized, however, that such contact pins do tend when loose to interengage endwise and so present difficult feeding problems.

In the accompanying drawings:

Fig. 1 is a perspective view of an illustrative machine in which the invention is embodied;

Fig. 2 is an enlarged perspective of a portion of the pin feeding mechanism shown in Fig. 1, the parts being in their initial positions;

Fig. 3 is a perspective similar to Fig. 2 but

showing the raceway units retracted and the pins being inserted;

Fig. 4 is a perspective of the disc and pins after assemblage in the illustrative machine;

Fig. 4a is another perspective of the final assemblage seen in Fig. 4;

Fig. 5 is an enlarged detail of one hopper, a portion being broken away to disclose internal construction;

Fig. 6 is a plan view of some of the parts seen in Fig. 5;

Fig. 7 is an enlarged longitudinal section of an intermediate portion of a raceway, indicating the percussion member;

Fig. 8 is a side elevation of the delivery end of a raceway unit and a portion of the percussion means;

Fig. 9 is a section taken on the line IX—IX of Fig. 8;

Fig. 10 is a section taken on the line X—X of Fig. 8;

Fig. 11 is a plan view of the delivery end of a raceway and detents;

Fig. 12 is an end view of the delivery end of a raceway with slotted detents;

Fig. 13 is a vertical section of parts in inoperative position at the rear or pin-upsetting station; and:

Fig. 14 is similar to Fig. 13 but showing the upsetting tools in operation on the pins.

In the illustrative machine for assembling two pairs of flanged electric contact pins 8, 8 and 10, 10 with a prepunched circular disc 12 of insulating material to form a base unit as shown in Fig. 4, there are circularly arranged a pin-loading station A (Figs. 1, 2 and 3), at the front of the machine, a disc loading station B on one side, an upsetting station C rearwardly, and a knock-off or unloading station D on the other side. These stations are spaced on a turret 14 rotatably mounted on a fixed housing 16. Except for the structure just noted and certain features to be hereinafter more particularly described, the general organization is essentially that of the machine disclosed in United States Letters Patent 1,932,420, granted on application of E. S. Nokes and relating to a gang fastener inserting machine. Accordingly, it will suffice if, in those aspects common to both machines, only a brief description is hereinafter set forth.

The housing 16 is secured to a frame 18 of the machine and contains some or all of a well-known form of means (not shown) required to rotate the turret 14 step by step clockwise (as viewed from above) in a horizontal plane. Pneumatic, mechanical, or other means may be employed for the purpose, it only being necessary that the turret be turned exactly 90° in each step, accurately and successively to register the aforementioned stations with respect to spaced operating tools about to be described. Preferably the arrangement is such that the turret turning occurs automatically as soon as the tools are simultaneously raised therefrom to nonobstructing inoperative positions. Affixed to the turret 14 and 90° apart thereon are four jig-blocks 20. Each block is provided with four vertical bores 22, 22 and 24, 24 adapted to receive the cylindrical bodies of the pins 8, 8 and 10, 10 respectively, the bores 22, 22 on one side being somewhat larger in diameter than the bores 24, 24 to accommodate the differently sized pins as commonly used in one type of contact assembly for commercial electron tubes. The cross-sectional shape of a bore thus closely corresponds with the lower portion of the pin

body to be received. Venting of the lower end of the bores assures easy and rapid pin insertion and subsequent ejection without interference by entrapped air.

Corresponding somewhat with the fastener inserting tools of the above-cited patent, inserting tools 26, 26 and 28, 28 (Figs. 1, 2 and 3) are relatively arranged to coincide with the pin-receiving bores when a jig-block 20 is at the pin loading station A. The inserting tools are secured to a plunger 30 arranged to slide in stationary guides 32, 32 bolted to an overhanging portion of the frame 18. Vertical reciprocations of the plunger 30 are effected by its crank connection (not shown) with a cam portion of a horizontal operating shaft 34 (Fig. 1) journaled in bearings in the frame 18. In accordance with common eyeleting practice, each inserting tool is provided with a central spindle 36 normally projected downwardly by a spring (not shown), the spindle being arranged to enter the barrel or hollow portion of a flanged pin in the delivery end of a raceway and to detach the pin from the raceway in consequence of retracting the latter.

A pulley 38 loosely mounted on the rear end of the shaft 34 is intended to be driven continuously by a belt 40 connected to the drive shaft of an electric motor 42. To establish driving connection between the pulley and the operating shaft 34 a suitable starting and stopping clutch indicated as a whole at 44 in Fig. 1 is provided. A rod 46 for operating the clutch is arranged to be connected to a treadle (not shown). As described in the patent referred to, the arrangement is such that releasing the treadle immediately after tripping the clutch 44 arrests the shaft 34 at the completion of each cycle.

The initial positions of the several tools, as well as parts of the cooperating feed mechanism hereinafter to be described, are indicated in Figs. 1 and 2. At station C, 180° from the pin loading station A, a set of four upsetting tools 48, 48 and 50, 50 (Figs. 3, 13 and 14) are arranged for vertical reciprocation, the tools 48, 48 being adapted to cooperate with the larger bores 22, 22, and the tools 50, 50 being adapted to cooperate with the pin receiving bores 24, 24. The upsetting tools are carried by a plunger 52 slideable in a bearing bracket 54 affixed to the frame 18, and the plunger 52 is actuated by a follower connected thereto (not shown) and engaging a cam 56 (Fig. 1) mounted on the shaft 34. A compression spring 58 bearing on the top of the bracket 54 and against a collar 53 which is vertically adjustable on the plunger 52 serves to maintain the follower in operative engagement with the cam 56. Secured within a vertical bore in the bottom of the plunger 52 and disposed centrally of the tools 48, 48 and 50, 50 is a compression spring 59 (Fig. 14) having a dual function later to be explained.

As shown in Fig. 1 two similar but oppositely arranged raceway units generally designated 60 and 62 are connected to the frame 18 by horizontal supporting pivots 61. The unit 60 is used to feed the larger pins 8, and the unit 62 feeds the pins 10. The delivery ends of the units are moved simultaneously toward and from each other with oscillatory motion about the pivots 61. The trains of mechanism for respectively operating the raceways in this manner, though here only partially shown, are fully described in the Nokes patent referred to above, it being sufficient for present purposes to state that each train 70 comprises a duplex cam 63 (Fig. 1) carried by

the shaft 34 for operating a horizontal rock shaft, the motions of which are communicated positively to a raceway unit.

The raceway assemblage 62 only will now be described, it being understood that the unit 60 is similar in structure and operation and differs merely in certain dimensions better to accommodate its pins. A hopper 64 is provided at the upper end of the unit 62 and has an inclined bottom 66 adjacent to which there is a pulley-operated, oscillatory pin-sweeping means such as a brush 68. Two downwardly curved tubes 70 respectively communicate with a port formed at the lower rim portion of the hopper. The ports are of a size to allow only endwise passage of the pins 10 from within the hopper, and the tubes have smooth internal surfaces arranged to provide a free flowing passageway wherein the pins fall endwise under the influence of gravity. An upstanding rib 72 extends radially along the bottom 66 and between the ports to separate the entry ends of the tubes 70. Also radially formed in the bottom 66 and extending on each side adjacent to the rib 72, so as to constitute channel extensions of the tubes 70, are grooves or gutters 74 respectively adapted to hold a single pin. It is to be noted that the upper ends of the tubes are substantially tangent to the hopper bottom 66 and that their lower portions 76, which actually are an intermediate portion of the raceway unit 62, are preferably more nearly horizontal. The portions 76 are each provided on their undersides with longitudinal slots 78 (Figs. 7 and 8) of a width to permit the pins 10 to be sustained by their flanges.

The unit 62 also comprises a stiffening web 80 to which the ends of the tubes 70 are affixed. While other means for effectively jarring the raceway portions 76 may be employed, for reasons to be explained, a highly satisfactory and simple arrangement is here provided. Use is made of the oscillatory movements of the web 80 to actuate a lever 82 pivotally secured to one of the guides 32 and carrying a weighted percussion member 84. A pin 86 fast to the web 80 is arranged to contact a V-shaped cam surface 88 formed in the lever 82 thereby to displace the latter against gravity. The pin and cam surface are relatively positioned to cause the member 84 intermittently to strike the horizontal portion 76 with sharp blows.

The lower portion of the web 80 supports a two-track chute 90 (Figs. 2, 3, 8 and 9) arranged to provide a further downwardly inclined course for the pins 10 emerging one by one from each of the slotted ends of the tubes 70. As it is highly desirable to maintain the tracks well filled with pins, it is preferable to have this lower part of the raceway unit rather steeply inclined; the lower portion of the chute 90 may advantageously be curved downwardly as best seen in Fig. 8 so that the delivery end may extend horizontally and thereby suspend the endmost pins approximately vertically.

To prevent the pins from prematurely escaping from the delivery end and in order that the endmost pins 10, 10 may be accurately registered with spindles 36 and inserting tools 28, 28, a detent 92 (Figs. 8, 10, 11) is pivotally supported on each side of the chute 90 by a vertical pin 94 held by lugs extending from the chute. A compression spring 96 seated in each side of the chute bears against one end of a detent 92 to hold its broad, inwardly curved, pin-engaging end in yielding engagement with a side of the pin 10 about to be delivered.

Preferably this pin-engaging end is provided with a slot 98 (Fig. 12) to accommodate the flange on the pin 10 and is accordingly adapted to engage substantially an entire side of the pin 10, thereby employing the downward pressure of the other pins in the track to aline the endmost pin accurately.

In the housing 16 is a stationary knock-off cam 97 (not shown except for a flat portion in Fig. 13). 10 An inclined and raised surface of this cam is arranged beneath station D to be engaged successively by the lower ends of advancing pins 99 respectively mounted for vertical sliding movement in bores formed centrally in each of the 15 jigs 20. To enable the completed assemblages to be cleared from the machine at station D after being lifted by the knock-off cam engagement with the pins 99 and thereby consecutively make 20 jig-blocks 20 available for reloading, a flat plate 100 is secured for rotation with the turret 14 and is adapted to receive the upper portion of each 25 of the blocks 20. A downwardly directed air stream, either of continuous or intermittent flow, may for example be aimed to strike the lifted assemblages and move them off the plate 100 toward a container.

In operating the illustrative machine, the hoppers 64 initially having been provided with flanged pins, the raceway unit 60 will convey the pins 8 and the raceway unit 62 will similarly supply the pins 10. Oscillating sweeps of the brush 68 carry the pins 10 against the sides of the rib 72, and one pin at a time is thereby deflected to fall in the groove 74 and is automatically alined with a tube 70 into which the individual pins slide endwise under the influence of gravity and the next sweep of the brush 68. A steady flow of pins in the tube 70 is desirable and normally obtained if the radius of curvature therein is not too small. 40 The pins do often tend to lodge within one another, however, regardless of whether their flanges happen to come near their respective lower or upper ends during this part of the feeding. It has been found that this tendency, primarily due to one end of each pin being of reduced diameter as shown in Fig. 4, may impede or obstruct flow, but when the pins reach the more nearly horizontal portions 76, endwise pressure between the pins is considerably relieved. Accordingly, the 45 intermittent blows of the percussion member 84 on these raceway portions are particularly effective in jarring the pins 10 to assure their being individually free to swing upright in the slots 78. The pins 10 are then successively supported by 50 their flanges as they proceed downwardly, the pins having been converted from relative endwise to sidewise formation as shown in Figs. 7 and 9.

Upon tripping the clutch 44 to start a cycle, the raceway delivery ends then being directly 55 above station A shown in Fig. 2, the inserting tools 26, 26 and 28, 28 are carried downward by the plunger 30. Each of the spindles 36 enters an endmost flanged pin which is individually separated from its track in a chute 90 upon withdrawal 60 of the latter. Two spindles 36, 36 enter the bores 22, 22, respectively, to guide the pins 8 for insertion by the tools 28, while two spindles 36, 36 enter the bores 24, 24, respectively, to guide the pins 10 for insertion by the tools 28. As the raceway 65 units 60, 62 are retracted and returned to initial positions, the members 84 are respectively actuated by pin 86 coaxing with cam surface 88 to cause percussion member 84 to strike the intermediate raceway portion 76, thereby assuring that 70 all flanged pins coming into the slotted portions 75

16 and chutes 90 have been jarred free of one another and converted by gravity from relative endwise to sidewise positions and that the lower portions of the raceways remain fully loaded. As soon as the pins have been positioned in the block at station A and are suspended therein by their flanges, the spindles 36 and inserting tools are returned to their initial positions and the turret 14 is rotated 90° to carry the loaded block to station B.

At station B the prepunched disc 12 is placed with its holes in register with the upwardly extending ends of the pins 8, 8 and 10, 10 just loaded as described and then pressed downwardly onto the pin flanges. This operation may be satisfactorily and safely accomplished by hand before the clutch 44 is again tripped or mechanical means (not shown) may supply and position the discs 12 as indicated. In the next revolution of the main shaft 34 permitted by the clutch 44 another block 20 is loaded at station A and the turret 14 is shifted 90° to carry the loaded pins and disc 12 from station B to station C.

As above indicated the pins 8, 8 and 10, 10 at station C are simultaneously upset and clenched against the upper surface of the disc 12 while the endmost pins over station A are being loaded. The spring 59 descends with, but ahead of, the plunger 52 and yieldingly engages the disc 12 to assure that it is accurately placed down flat on the four pin flanges before upsetting action by the tools 48, 48 and 50, 50 commences. When these upsetting tools are again raised the spring 59 serves as a stripper and enables the completed assemblage to maintain its position in the block 20 until the upset pins engage the knock-off cam below station D. The assemblage will be automatically raised to rest momentarily on the top of the plate 100 and then, either by centrifugal force, a blast of air, or other means not shown, will be transferred from the machine.

Having described my invention, what I claim as new and desire to secure by Letters Patent of the United States is:

1. A machine for processing flanged pins comprising a pin hopper, an oscillatory raceway curvedly extending generally downward from the hopper freely to convey therefrom a series of flanged pins endwise, said raceway including an intermediate portion which is more nearly horizontal and provided with a longitudinal slot, the slot being arranged and adapted to enable the pins to be suspended therein by their flanges, and means including a percussion member engageable with said intermediate portion for intermittently jarring the pins entering therein, said means being operated by the oscillatory movements of the raceway.

2. A machine for inserting flanged pins comprising a hopper therefor, a vertically reciprocable inserting tool, a swingable raceway unit in communication with said hopper and adapted to conduct the pins endwise therefrom one at a time, said unit including a generally downwardly extending tube having an intermediate portion and a delivery end portion, said portions being substantially horizontal and having continuative longitudinal slots in which the pins may be suspended by their flanges for sidewise movement, the delivery end portion being movable toward and from the path of said tool for cooperation therewith, and a detent pivotally related to the raceway delivery end and slotted to accommodate a flange on the pins and position the endmost pin vertically before release thereof to said tool.

3. A machine as set forth in claim 2 further characterized in that means are provided for swinging the raceway unit in time relation to the movements of the tool, and a jarring device operable by said means is engageable with said intermediate portion.

4. A flanged-pin handling machine comprising a frame, a reciprocable pin-inserting tool, a hopper, means for feeding flanged pins from the hopper to a position coincident with the path of said tool, said means including a raceway unit pivotally mounted on the frame for oscillation of its delivery end toward and from said path, the unit having a generally downwardly extending tube in communication with the hopper, the upper inclined portion of said tube having a passageway of a size adapted to conduct the pins endwise only and the remainder of the tube having a longitudinal slot adapted to suspend the pins by their flanges for sidewise movement in a row, a jarring device engageable with the slotted portion of said tube, and mechanism for oscillating the raceway, said mechanism being effective to operate the jarring device to insure uniform side-by-side alinement of the lowermost pins.

SYLVESTER L. GOOKIN.
